UNITED STATES PATENT OFFICE

NORMAN W. FILE, OF LYNCHBURG, VIRGINIA

SURGICAL APPLIANCE

Application filed April 28, 1931. Serial No. 533,522.

This invention relates to surgical appliances, and has for its object to provide a combination of haemostat and ligator, the latter being detachably and slidably mounted upon the haemostat in such manner as to permit the combined device to be brought to the bleeding point by the use of one hand only, the loop of the ligature encompassing the jaws of the haemostat, and as the haemostat has been clamped upon the bleeding point, to permit the loop to be shed from the nose of the haemostat about the bleeding vessel by sliding the ligator forwardly along the haemostat. The invention contemplates as well, a mode of operation in which the combined device is applied to the point of bleeding by one hand as described, and then separated and subsequently manipulated as separate instruments in the holding of the vessel and tying it off.

Another object of the invention is to provide a ligator having means adapting it to be structurally associated with a haemostat while closing the bleeding vessel, the haemostat acting as a guide for the loop of the ligature, leading it to the tying off point of the vessel in the subsequent manipulation of the ligator, whether or not the ligator is kept mechanically associated with the haemostat or operated separated therefrom.

A further object of the invention resides in the novel construction of the ligator itself.

Other objects of the invention will appear as the following description of a preferred and practical embodiment thereof proceeds.

In the drawings in which the same characters of reference have been employed throughout the several figures to designate identical parts:

Figure 1 is a plan view of the combined ligator and haemostat, parts being broken away;

Figure 2 is an underneath plan view of

the combined instrument, the handles of the haemostat being omitted;

Figure 3 is a side elevation partly in section on an enlarged scale showing the working ends of the haemostat and ligator and the sliding connection between the two instruments; and

Figure 4 is a section taken along the line 4—4 of Figure 3.

Referring now in detail to the several figures the numeral 1 represents a haemostat of usual construction, that is to say, it comprises a pair of handles 2 and 3 pivoted scissors-like at an intermediate point 4 and having cooperating jaws 5 and 6 preferably formed with finely serrated meeting faces 7 between which the bleeding vessel is adapted to be clamped. The handles are made of resilient material, one being provided with a ratchet lug 8 and the other with a hook lug 9 engaging with the ratchet to retain the jaws of the haemostat closed with varying degrees of pressure.

The haemostat as above described is conventional and is not a part of the present invention per se, but only in novel combination with the ligator.

The ligator comprises a shank 10 having a bore 11 in its forward portion opening on top of the shank at the point indicated at 12 in Figure 1, said bore receiving a ligature 13 which protrudes from an orifice 14 at the forward end of the ligator. Rearwardly of the opening 12, the shank of the ligator carries a slidably mounted cleat 15 about which the free end of the ligature is adapted to be wound and retained. The cleat 15 is mounted on a carriage 16 having a cylindrical bore through which the posterior portion of the shank 10 extends. The carriage 16 on its lower face is provided with guide pins 17 and 18 sliding in a groove 19 formed on the under-side of the shank 10. The groove 19 is provided at its base with a leaf spring 20 or its equivalent against which the ends of the pins 17 and 18 bear. Said

leaf spring imposes a resilient resistance to the movement of the carriage 16 and acts as a brake.

The carriage is provided with finger rings 21 and the rearward end of the shank 10 of the ligator is provided with a finger ring 22. The latter ring is preferably formed with a socket 23 receiving the end of the shank 10 and being secured thereto by a thumb screw 24. 5 When the finger ring 22 is removed, the end of the slot 19 is thus opened permitting the carriage 16 with its appurtenant parts to be removed from the ligator to facilitate cleansing and sterilizing of the instrument. At an 10 intermediate point the ligator is provided with a channeled guide 25, the side flanges of which are adapted to freely embrace one of the handles of the haemostat. Figure 3 shows the ligator thus mechanically associated with the handle 3 of the haemostat. The 15 broken line representation of the channeled guide 25 shows that it is slidable upon the haemostat and when it is in its forward-most position, the forward end of the ligator is in 20 the broken line position shown in Figure 3 in which position the loop 26 of the ligature is shed from the jaws of the haemostat around 25 the stump of the bleeding vessel.

In operating the combined appliance, the 30 ligator is mounted upon the haemostat with the guide 25 embracing a handle of the haemostat and the loop of the ligature placed about the jaws of the haemostat as shown in Figures 1, 2 and 3. The haemostat is then brought to 35 the point of bleeding with the ligator mounted thereupon, only one of the surgeon's hands being employed, leaving the other hand free for any other desired manipulation. The haemostat is clamped upon the bleeding stump 40 and the ligator is then slid forward on the haemostat to the dotted line position so that the loop of the ligature becomes removed from the haemostat and surrounds the bleeding vessel below the point of application of 45 the haemostat. It is assumed that the knot by which the loop of the ligature is formed is a slip knot so that by pulling the cleat 15 rearwardly, the ligature is drawn through the ligator tightening the loop about the 50 point of bleeding. The ligature may then be cut off and the haemostat released. In the manipulation of the appliance as above described, the haemostat serves as a guide for guiding the loop 26 of the ligature to the 55 point of bleeding and around the vessel which is to be tied off. It is not necessary however, that the ligator should remain slidably attached to the haemostat during the tying off operation. If desired, as soon as the 60 bleeding vessel has been clamped, the ligator may be lifted from the haemostat and manipulated as a separate instrument, although in the separate manipulation the haemostat still acts as a guide for leading the loop of the 65 ligature to the proper point for tying.

In addition to the advantage of being able to approach the point of bleeding with both instruments, using only one hand, and having the haemostat act always as a guide for the loop of the ligature, the instrument has the 70 additional advantage of being easy to keep clean and sterile since the bore through the ligator is but little larger than the diameter of the ligature, practically preventing the entrance of blood into said bore. The ease with 75 which the ligator may be removed from the haemostat, and the removable relation of the cleat and carriage 16 to the shank 10 of the ligator permits the several parts to be separated facilitating the cleansing of the same. 80

While I have in the above description disclosed a preferred and practical embodiment of the invention, it is to be understood that the details of construction as described are merely by way of example and are not to be 85 construed as limitative in their bearing upon the scope of the invention as claimed.

What I claim is:

1. A ligator including a shank having the bore in the anterior part thereof opening in 90 the end of said ligator and laterally, rearwardly of said end, and a cleat slidably mounted upon said ligator for receiving the free portion of a ligature passing through the bore of said shank, and for tautening said 95 ligature.

2. Ligator comprising a shank, said shank being formed with a bore in its anterior portion opening in the end of said shank and laterally, rearwardly of said end, means on said 100 shank adapting it to be detachably and slidably mounted on a haemostat, a sliding cleat on said shank for receiving the free portion of said ligature and tautening the loop of said ligature, a sliding carriage on which said 105 cleat is mounted, said shank and carriage being provided with inter-engaging elements for preventing rotation of said carriage.

3. Ligator as claimed in claim 2, the shank being formed with a groove and the sliding carriage being provided with guiding pins 110 extending into said groove, and a spring in said groove engaged by said pins and acting as a brake for said carriage.

4. Ligator as claimed in claim 2, said shank being formed with a groove opening into the posterior end of said shank, guiding pins extending from said carriage into said groove, a spring in said groove engaged by said pins 115 forming a brake for said carriage, and a detachable handle on the end of said shank normally closing the open end of said groove, said carriage being removable from said shank through the open end of said groove upon removal of said handle.

5. A ligator adapted to be slidably and detachably secured to a haemostat, including a channeled guide adapted to slip over a longitudinal member of said haemostat, said ligator comprising a shank having a bore in the 120

anterior part thereof opening in the end of said ligator and laterally at an intermediate point, and a cleat slidably mounted upon said ligator rearwardly of said lateral opening for receiving the free portion of a ligature passing through the bore of said shank, and for tautening said ligature.

6. Ligator as claimed in claim 2, the shank being formed with a groove and the sliding carriage including a guiding portion extending into said groove, and a spring in said groove engaging said guiding portion and acting as a brake for said carriage.

In testimony whereof I affix my signature.
